D. H. WILSON ET AL.
SUPERHEATER PIPE CONNECTION AND METHOD OF MAKING THE SAME.
FILED OCT. 2, 1920.

UNITED STATES PATENT OFFICE.

DAVID H. WILSON, OF WORTENDYKE, NEW JERSEY, AND JAMES E. FULLER, OF FREDONIA, NEW YORK; E. PAULINE WILSON ADMINISTRATRIX OF SAID DAVID H. WILSON, DECEASED.

SUPERHEATER PIPE CONNECTION AND METHOD OF MAKING THE SAME.

Application filed October 2, 1920. Serial No. 414,311.

To all whom it may concern:

Be it known that we, DAVID H. WILSON, a citizen of the United States, and a resident of Wortendyke, county of Bergen, and State of New Jersey, and JAMES E. FULLER, a citizen of the United States, and a resident of Fredonia, county of Chautauqua, State of New York, have invented certain new and useful Improvements in Superheater 10 Pipe Connections and Methods of Making the Same, of which the following is a specification.

Our invention relates to a method of forming nipples upon the ends of metal tubes 15 and is particularly applicable to the tubes of superheaters for steam boilers. Our invention is herein disclosed as applied to that type of superheaters in which the tubes are connected to suitable headers. One object of 20 our invention is to provide an improved nipple which will form a tight joint at the header and which will be cheap, durable, easily assembled, with a homogeneous crystalline structure free from cracks and capable 25 of withstanding high temperatures without burning out. Other objects and advantages will hereinafter appear.

In the accompanying description, we have disclosed one method of carrying out our 30 invention, reference being had to the accompanying drawing in which:

Figure 1 represents a section of a superheater pipe stock upon the end of which a sleeve of additional metal stock has been 35 fitted.

Figure 2 represents the pipe stock and sleeve shown in Figure 1 after the first heating and forging operation has taken place showing the manner in which the 40 shoulder is molded.

Figure 3 shows the same pipe stock and sleeve in its final condition after the second heating and forging operation, showing the shoulder further upset and the bead which 45 has been formed upon the end of the tube.

Figure 4 shows one of the superheater tubes in operative position with its end clamped into the orifice of the header.

In the manufacture and use of superheaters for steam boilers, considerable trouble has been experienced in fitting the 50 ends of superheater tubes into the superheater headers. It has been found difficult to make a tight joint capable of withstanding the

intense heat to which the parts were subjected without burning out. In order to avoid this difficulty, superheaters have been made in which the ends of the tube stock have been thickened by crimping and molding into the form of a hollow ball joint, which 60 were then clamped tightly to the header orifices. According to this crimping method, an annular groove or crimp was first formed in the tube stock near the end. The metal in this crimped portion was then squeezed 65 together and folded back to form an annular clamping shoulder. The end of the tube was also expanded and folded back into a bead. The above operations were carried out in a suitable upsetting machine in which 70 the heated metal was subjected to pressure between plungers and dies. The superheater tubes formed by the above method were found to be weak, owing to the existence of 75 permanent cracks and laminations sometimes called "cold-shuts" in the metal of the tube which were necessarily formed during the above mentioned crimping and folding operations.

In practice many failures occurred in the 80 thickened bead and shoulder portions of these tubes and upon examination, it was found that the metal of the tube was "fatigued" and had a dangerous crystalline structure caused by the excessive deformation to which the metal gathered up from the stock in the tube was subjected. Moreover, the microscopic structure of the metal was found to be heterogeneous and the metal 85 was also brittle causing frequent accidents 90 and making constant shut downs for renewals necessary. The formation of "cold-shuts" was particularly frequent when the diameter of the tube was either smaller or larger than standard, in which case large 95 cracks visible without a microscope were often formed at the shoulder or bead.

Another disadvantage in the above method is that an excessive number of distinct operations and heats were required 100 which were very detrimental to the metal structure.

According to the method which we have discovered, the end of a superheater tube may be fashioned in only two operations and 105 the above disadvantages can be entirely avoided. Moreover by our method the strength of the ball joints or nipples will

be greater than the strength of the tube stock itself.

In carrying out our improved method the first step consists in fitting a sleeve 1 of 5 additional metal stock upon the end of a tube 2, as clearly indicated in Figure 1. The end of the tube 2 with its sleeve is then heated to a forging temperature and placed in the die of any suitable type of 10 upsetting machine, similar to that employed in the method previously described. A suitable plunger or mandrel is then forced into the interior of the tube and pressure applied, causing the added stock of the sleeve to become welded to the pipe stock and upsetting a shoulder 3 at the rear of said sleeve without in any way crimping or distorting the original tube stock itself, the metal for 15 the shoulder being entirely gathered from the sleeve.

The next operation consists in re-heating the end of the tube to a forging temperature and again placing it into the upsetting machine. A second plunger or mandrel of 20 a slightly different form is then forced inside of the tube and pressure applied upsetting the forward portion of the sleeve into the form of a bead 4 of approximately the proper size to fit the bevelled socket 5 of 25 the superheater header 6, the latter being shown in Figure 4. In this operation some 30 of the metal of the end of the pipe will be turned or drawn outwardly so as to form a part of the outer face of the ball or nipple.

The beaded tip 4 of the nipple may then be ground to accurately fit the bevelled socket 5 of the header conduit and the rear of the shoulder 3 may be machined in a 40 lathe so that it will fit the collar 7 of the jaw 8 of an adjustable clamp. The other jaw of the clamp (not shown) bears upon the opposite side of the header.

While we have given an illustration of 45 the application of our invention to the manufacture of superheater tubes it is obvious that the invention may be employed equally well for the formation of a socket joint or nipple upon the end of any other type 50 of metal tube and that it is not to be limited to superheater tubes. We desire it to be understood that the method herein disclosed has been given merely by way of a specific 55 example and that various modifications may be made therein within the general principles and scope of the invention.

We claim:

1. A superheater tube having a cylindrical inner surface throughout its length, provided upon its outer surface with an upset annular shoulder, said shoulder being

formed upon the outside of said tube from an additional supply of metal stock.

2. A method of forming a nipple upon the end of a metal tube which comprises 65 providing said tube with a concentric sleeve of additional metal stock, applying heat and pressure to said tube and sleeve to force a part of the sleeve into an annular shoulder, and applying heat and pressure to the outer 70 end of said tube and sleeve to force the outer end of said sleeve into a curved bead or ball.

3. A method for forming a ball joint upon the end of a metal tube adapted to be 75 clamped into a socket opening in a conduit, which comprises providing said tube with a concentric sleeve of additional metal stock, forming a shoulder on said tube from the metal of said sleeve in one forging operation 80 and a bead or ball at the end of the tube in a second forging operation.

4. A method of forming a ball joint or nipple upon the end of a metal tube, to enable said tube to be clamped into a socket 85 opening in a conduit, which comprises providing said tube with a concentric sleeve of additional metal stock, forming a shoulder on said tube from the metal of said sleeve in one forging operation and a bead 90 or ball at the end of the tube in a second operation and machining the ball to fit the socket opening.

5. A method for forming a ball point or nipple upon the end of a tube to enable 95 said tube to be clamped into a socket opening in a conduit, which comprises providing said tube with a concentric sleeve of additional tube stock, upsetting said sleeve stock to form a shoulder and an end bead and 100 welding said sleeve, tube, bead and shoulder into a homogeneous mass free from cracks, said nipple having a strength at least equal to that of the cylindrical portion of the tube.

6. A method of producing a nipple or ball joint upon the end of a metal tube which consists in providing said tube with a sleeve of additional metal stock and applying heat and pressure to force a part of the metal 110 of said sleeve into the form of a nipple and to molecularly unite said sleeve and tube.

7. A method of producing a nipple or ball joint upon the end of a metal tube which consists in providing said tube with a sleeve 115 of additional metal stock and applying pressure to force a part of the metal of said sleeve into the form of a nipple.

In testimony whereof, we have affixed our signatures to this specification.

DAVID H. WILSON.
JAMES E. FULLER.
